(57) **CLAIM**

The ornamental design for a handle for handheld cleaning appliance as shown and described.

DESCRIPTION

Handle for handheld cleaning appliance

1.1 is a front view of a first embodiment of a handle for handheld cleaning appliance, showing our new design;

1.2 is a back view thereof;

1.3 is a left view thereof;

1.4 is a right view thereof;

1.5 is a top view thereof;

1.6 is a bottom view thereof;

1.7 is a left, top perspective view thereof;

1.8 is a right, top perspective view thereof;

2.1 is a front view of a second embodiment of a handle for handheld cleaning appliance, showing our new design;

2.2 is a back view thereof;

2.3 is a left view thereof;

2.4 is a right view thereof;

2.5 is a top view thereof;

(Continued)

2.6 is a bottom view thereof;
2.7 is a left, top perspective view thereof; and
2.8 is a right, top perspective view thereof.
